ELECTRIC FAN

John G. Macdonald, Toronto, Ontario, Canada

REISSUED

Application September 3, 1935, Serial No. 39,057

1 Claim. (Cl. 230—274)

This invention relates to an improvement in electric fans, of the character utilizing a series of vanes for deflecting the air currents from the fan which vanes are oscillated by a mechanism coacting with the motor-driven fan.

My improvement consists of a simplified oscillating mechanism to move the deflecting vanes, a suitable metal case having special design features to surround the working mechanism of the fan so as to act as a support and also a protection all of which features are constructed to enhance the appearance of the fan.

Further objects of the invention are to provide an electric fan of the character referred to that is strong, compact and durable, thoroughly reliable for its intended purpose, very light in construction, having very few parts to need repair and comparatively inexpensive to manufacture.

With the foregoing and other objects in view the invention consists of a novel construction, combination and arrangement of parts as will be hereinafter more specifically described and illustrated in the accompanying drawings, wherein is disclosed an embodiment of the invention, but it is to be understood that changes, variations, and modifications may be resorted to without departing from the spirit of the claim hereunto appended.

In the drawings wherein like reference characters denote corresponding parts throughout the several views:—

Figure 1 is a front elevation of the improved electric fan embodying the principles of the present invention.

Figure 2 is a rear elevation thereof showing parts in vertical section.

Figure 3 is a horizontal section taken substantially on the line 3—3 of Figure 4 and looking downwardly.

Figure 4 is a detailed vertical section thereof having parts broken away.

Figure 5 is a perspective view of one of the deflecting vanes removed from the casing.

Figure 6 is a fragmentary perspective view of the connecting link for oscillating the deflecting vanes.

Figure 7 is an enlarged vertical section through the pivotal connection between the supporting arms and the casing.

Figure 8 is an enlarged side elevation of the eccentric connection between the connecting link and the drive shaft.

Figure 9 is a perspective view of the disk on the terminal of the drive shaft.

Referring to the drawings in detail the numeral

10 indicates an oblong base which may be formed of metal or bakelite. Carried by the base is a conventional switch arm 11 of a switch not shown, for controlling the electric current that drives the fan. Rising from the base at each end are 5 the vertical supporting arms 12. To enhance the appearance and add symmetry and balance I prefer to make the casing A of a square configuration. This casing is formed of light sheet metal having integral top and bottom walls 13, 14, respectively, and side walls 15. The casing A is open at forward and the rear ends to allow currents of air to pass therethrough. The handle 16 is secured to the top wall 13. On intermediate portions of the side walls 15 spaced horizontal 10 ribs 17 are formed to enhance the appearance of the fan. Across the rear open end of the casing A are the crossed braces 18. The outer ends of the vertical portions of the crossed braces are respectively joined with the top and bottom walls 20 of the casing respectively. The ends of the horizontal portion of the crossed braces are respectively joined to the opposite side walls 15. The crossed braces merge with each other at the center of the rear open end of the casing. Where 25 the crossed braces 18 merge at the center there is supported an electric motor 19 and the motor extends into the casing. The motor 19 drives the fan 20. On the rear side at the juncture of the crossed braces 18 there is a gear casing 21 30 having a flange 22 bolted as at 23 to the crossed braces. The armature shaft of the electric motor 19 is formed with a rearward extension which projects into the gear housing 21 and is formed with a worm gear 24. Within the gear housing 21 35 is a transverse horizontal shaft 25 journaled at its opposite ends in the walls of the housing. On an intermediate portion of the shaft 25 is a gear 26 which meshes with the worm gear 24.

The drive shaft for oscillating the deflecting 40 vanes is indicated at 27 and this shaft is arranged in a vertical position. The lower end of the shaft 27 extends vertically through the gear housing 21 and has journal bearings on the top and bottom wall of the housing. On the portion of drive 45 shaft 27 within the housing there is a gear 28 which meshes with a worm gear 29 on the shaft 25. The upper end of drive shaft 27 terminates below the top wall 13 and on the outside of the casing. Near the top of the upper vertical portion of cross brace 18 is a bearing bracket 30 that supports the upper end of the drive shaft 27. Above the bearing bracket 30 there is a disk 31 secured to the terminal of the drive shaft 27. The disk is disposed in a horizontal plane. At 50 55

a portion of the disk 31 there is a radially disposed slot 32 that provides for adjustment of the connecting rod as will hereafter appear.

Across the bottom wall 14 of the casing is secured 5 a bearing bar 33 inside the casing and to the rear of the forward open end thereof. The center of the bar is formed with a raised rib 34 and along the rib 34 are spaced openings. On the top wall 13 is secured a bar 35 similar in all respects to the bar 33. Arranged between the bars, forwardly of the fan 20, and to the rear of the open forward end of the casing are the spaced deflecting vanes 36. The deflecting vanes oscillate on trunnions 37 and these trunnions are journaled in the openings in the raised ribs formed in the bars 33 and 35. The deflecting vanes oscillate on a vertical axis. Each vane 36 is formed with an extension 38 on the rear upper corner which extension terminates in a sleeve 39.

There is a T-shaped connecting bar or rod for oscillating the vanes and this connecting rod is arranged under the top wall 13 above the ends of the fan blades. The stem of the connecting rod is indicated at 40 and extends rearwardly through an opening in the upper vertical cross brace. The rear end of the stem 40 is formed with a slot 41. The shank 42 of a bolt extends through the slot 41 in the stem of the connecting rod and also through the slot 32 in the disk 31. The head 43 of the bolt bears on the upper face of the stem 40. Between the stem 40 and the disk 31 there is a washer 44 surrounding the shank of the bolt, and this washer spaces the disk from the stem. The lower end of shank 42 projects below the lower face of disk 31 and carries a nut 45 thereon. To exert a tension on the bolt there is a coiled spring 46 bearing at one end against the disk 31 and at the other end against the nut 45. Tension on the spring 46 is sufficient to retain the bolt in any set position along the slot 32 whereby the stroke of the connecting rod may be regulated for controlling the oscillation of the deflecting vanes.

The forward end of the stem 40 of the connecting rod merges with the center of the cross-head 47 and this cross-head 47 carries depending pins 48 which are journaled in the sleeve 39 on the upper corners of the deflecting vanes 36. It will be seen that as the disk 31 revolves the connecting rod having an eccentric connection there-

with by means of the bolt or shank 42 the connecting rod will move back and forth in a horizontal plane thereby oscillating the vane which deflects the current of air back and forth.

The entire casing A is adjustable on a transverse horizontal axis. To accommodate this adjustment there is a relatively large rectangular opening 50 in the bottom wall. The supporting arms 12 rise from the base and extend through this opening 50. The free ends of the arms 12 terminate adjacent the side walls at approximately the center of gravity of the casing. To provide a pivotal connection between the arms 12 and the casing, each side wall 15 has secured thereto an inwardly extending pivot pin 51 threaded at 52 on its inner free end. Spaced washers 53, 54 are mounted on the pin in spaced relation. The pin 51 extends through a relatively large opening 55 in the upper end of arm 12. On each side of the opening 55 in each arm there is a rubber disk 56 and each disk is formed with a central aperture through which the pin 51 extends. These rubber disks 56 are clamped to the upper end of the arms 12 by a nut 57 bearing on the outer washer 53. The rubber disks 56 are clamped between the washers 53 and 54 and this construction forms the pivotal connection between the arms 12 and the side wall 15 of the casing.

Having described my invention what I claim is:—

In an electric fan, a base, a casing including side walls and open at each end, a pair of supporting arms rising from the base and pivoted at their free ends to intermediate portions of the side walls, crossed braces carried by the walls of the casing bridging one open end of the casing, a motor driven fan carried by the cross braces and surrounded by the walls of the casing, air deflecting vanes pivoted to oscillate on a vertical axis adjacent the other open end of the casing and forwardly of the fan, a gear housing carried by the cross braces, a vertical shaft journaled at its lower end in the casing, means coacting with the motor driven fan to rotate the shaft, a connecting rod pivoted at one end to the vanes, and an eccentric connection between the shaft and the other end of the connecting rod to oscillate the deflecting vanes.

JOHN G. MACDONALD.
